UNITED STATES PATENT OFFICE.

CHARLES E. MORRIS, OF LEAVENWORTH, KANSAS, ASSIGNOR OF ONE-HALF TO CHARLES W. PARKER, OF LEAVENWORTH, KANSAS.

MAGNETIC GUN.

1,324,204.

Specification of Letters Patent.

Patented Dec. 9, 1919.

Application filed February 23, 1916. Serial No. 79,889.

To all whom it may concern:

Be it known that I, CHARLES E. MORRIS, a citizen of the United States, residing at Leavenworth, in the county of Leavenworth 5 and State of Kansas, have invented a certain new and useful Improvement in Magnetic Guns, of which the following is a specification.

My invention relates to improvements in 10 magnetic guns.

The object of my invention is to provide a gun from which a projectile may be hurled by magnetic force.

A further object of my invention is to 15 provide a magnetic gun through and from which a magnetizable projectile may be projected by means of a series of magnetic fields which are consecutively energized and deenergized.

20 Still another object of my invention is to provide means by which such energizing and deenergizing may be controlled by the projectile itself.

Still another object of my invention is to 25 provide a magnetic gun which is arranged to impart axial rotation to the projectile.

A further object of my invention is to provide a magnetizable projectile so constructed that axial rotation will be imparted to it 30 when fired from a magnetic gun of the proper construction.

The novel features of my invention are hereinafter fully described and claimed.

In the accompanying drawing which illustrates the preferred embodiment of my invention,

Figure 1 is a vertical longitudinal central sectional view of a magnetic gun embodying my improvement. In this view, the projectile 40 is shown mounted in the initial position.

Fig. 2 is a rear elevation of the gun.

Fig. 3 is a side elevation of the barrel.

Fig. 4 is an end view of the barrel.

Fig. 5 is a side elevation of the projectile.

45 Fig. 6 is an end view of the projectile.

Fig. 7 is a diagrammatic view of the circuit, in which are located the helices and the barrel of the gun.

Similar reference characters designate 50 similar parts in the different views.

1 designates a base on which is rotatably supported on a vertical axis a U-shaped

standard 2, between the arms of which is pivoted on a horizontal axis by trunnions 3 a barrel supporting member 4 having two 55 upwardly extending arms 5 at the front and rear ends thereof respectively in which is mounted a barrel 6 provided with a central longitudinal circular hole 7, which forms the passage for the magnetizable projectile 8.

The barrel 6 is preferably polygonal in cross section, the barrel shown in the drawing being a tube which is square in cross section on its periphery and which is in the 65 form of a square rod which has been twisted, as shown in Fig. 3, in the spiral form.

Encircling the barrel 6 and disposed one in front of the other and separated from each other by insulating collars 9 are a 70 series of helices 10, 11, 12 and 13. The windings of these helices tightly embrace and conform to the barrel. Those portions of the windings next to the corners of the barrel are farther from the axis of the barrel, than those portions which lie against the flat sides of the barrel. By reason of this construction, a spiral magnetic field is provided which serves to rotate the projectile 75 on its axis.

80 The projectile 8 adapted to be used in this gun is provided with a series of spirally arranged peripheral ribs 14 disposed so as to correspond and coincide respectively with the spiral magnetic fields, created when the 85 helices 10, 11, 12 and 13 are energized. By reason of this construction, the ribs 14 will be attracted by these spiral lines of force, and as the projectile passes through the barrel 6, it will have, axial rotation imparted 90 to it.

In order that the helices 10, 11, 12 and 13, which respectively form solenoid coils may be consecutively energized and deenergized, so as to consecutively magnetize and attract 95 the projectile 8, so as to cause the latter to travel through and be projected from the barrel 6, the following described mechanism may be employed.

Secured in the barrel 6 and extending upwardly therefrom are a series of tubes 15, 16, 17 and 18, in which are respectively mounted a series of vertically slidable pins 19, 20, 21 and 22, which are normally forced by a plu-

rality of springs 23 located respectively one in each tube 15 to 18 to positions in which their lower ends will extend into the opening 7 so as to be consecutively struck by the 5 projectile 8. The upper ends of the springs 23 are respectively held in place by caps 24 mounted in the upper ends of the tubes 15 to 18 respectively.

The tubes 15 to 18 are so arranged relatively to the coils 10 to 13, that the projectile 8 in striking and leaving the pins 19 to 22 will cause the coils or helices to be consecutively energized as the projectile enters said coils, and to be deenergized, after the 15 projectile has passed more than half through the different coils.

To effect this, the parts are connected in an electrical circuit which is arranged in the following manner.

20 Referring to Fig. 7, 25 designates an electrical generator, as for example, a battery, which at one pole is connected by a conductor 26 with the barrel 6, which is electrically conductive. Connected to the other 25 pole of the battery 25 is a conductor 27 which is respectively connected to one set of ends of the helices 10 to 13 by conductors 28, 29, 30 and 31.

The other set of ends of the helices 10 to 30 13 are respectively connected to the caps 24 and thereby through the springs 23 with the pins 19, 20, 21 and 22 by conductors 32, 33, 34 and 35.

When the projectile 8 is inserted in the 35 barrel 6, the current will pass from the battery 25 by the conductors 27 and 28, thence through the coil 10, and thence by way of conductor 32, pin 19, projectile 8, barrel 6, and conductor 26 back to the battery 25.

40 The coil 10 will thus be energized and will draw into it the projectile 8. By the time the projectile has passed about three-quarters way through the coil 10, it will strike the pin 20 and the coil 11 will be energized 45 by reason of the current passing from the conductor 27 through the conductor 29, coil 11, conductor 33 and pin 20, from which the current will pass through the projectile 8 and back to the battery in the manner already described. In the meantime, the connection between the projectile 8 and the pin 19 will be broken, and the coil 10 will be thus deenergized and will offer no resistance to the further forward progression of the projectile.

55 In like manner, the coil 11 will be deenergized when the projectile strikes the pin 21 and becomes disconnected with the pin 20.

In a similar manner, the coils 12 and 13 60 will be energized and deenergized as the projectile strikes and leaves the pins 21 and 22, the current passing consecutively from the conductor 27 through the conductors 30 and 31 and the coils 12 and 13 and conductors 34 and 35 and pins 21 and 22.

The projectile will thus be forced through and discharged from the barrel 6.

In order that the electrical contact may be good between the projectile 8, pins 19 to 22 and the barrel 6, the grooves between the 70 ribs 14 may be filled with some non-magnetic good conductor, such as brass or copper, 36.

The barrel support 5 may be provided with a handle 37 for swinging it on its vertical axis.

75

The barrel support 5 is provided with a projection 38 having holes 39 concentric with one of the trunnions 3. A bolt 40 mounted in one of the arms of the standard 2 is adapted to enter any one of 80 the holes 39 for holding the barrel 6 in the position to which it may be swung with the support 5.

I do not limit my invention to the structure shown and described as modifications, 85 within the scope of the appended claims, may be made without departing from the spirit of my invention.

What I claim is:—

1. A magnetic gun having a projectile 90 guide and provided with means for forming a spiral magnetic field adapted for projecting a projectile along and from said guide, and for imparting axial rotation to the projectile.

95

2. A magnetic gun having a projectile guide and provided with means controllable by a projectile for forming a spiral magnetic field adapted for projecting the projectile along and from said guide and for imparting axial rotation to the projectile.

100

3. A magnetic gun having a projectile guide and provided with electro-magnetic means for forming a spiral magnetic field adapted for projecting a projectile along and from said guide and for imparting axial rotation to the projectile.

105

4. A magnetic gun provided with means for establishing one in front of the other a plurality of spirally disposed magnetic fields arranged to project a projectile from the gun and to impart thereto axial rotation.

110

5. A magnetic gun provided with means for consecutively establishing one in front of the other a plurality of spirally disposed magnetic fields, arranged to impart axial rotation to a projectile and project it from the gun.

115

6. A magnetic gun provided with means for consecutively establishing one in front of the other a plurality of spirally disposed magnetic fields, and for consecutively demagnetizing the fields in the rear as those in front are established, the fields being arranged to operate upon and project a projectile from the gun, and for imparting axial rotation to the projectile.

120

7. A magnetic gun provided with means controllable by a projectile for consecutively establishing one in front of the other a plu-

125

130

- rality of spirally disposed magnetic fields arranged to operate upon and project a projectile from the gun, and for imparting axial rotation to the projectile.
5. 8. A magnetic gun provided with means controllable by a projectile for establishing consecutively one in front of the other a plurality of spirally disposed magnetic fields, and for consecutively demagnetizing 70 the fields in the rear as those in front are established, the fields being arranged to operate upon and project the projectile from the gun, and to impart axial rotation to the projectile.
15. 9. A magnetic gun provided with a projectile guide and having means for establishing around said guide a magnetic field arranged to operate upon a projectile in the guide for projecting the projectile therefrom, the arrangement of the magnetic field being such that the lines of greatest force operating upon the projectile will be disposed spirally. 80
20. 10. A magnetic gun having a projectile 85 guide, means for establishing around said guide a magnetic field arranged to have its greatest lines of magnetic force adapted to operate upon a projectile in the guide in spiral lines encircling the axis of the guide, and a projectile having spirally arranged portions arranged to correspond respectively to and to be operated upon by said spiral lines of force.
11. A magnetic gun provided with means 90 for consecutively establishing one in front of the other a plurality of magnetic fields, a projectile guide encircled by said fields, the latter having their lines of greatest force arranged spirally around the axis of the 95 guide, and a projectile having means by which said spiral lines of force impart rotation to the projectile.
12. A magnetic gun provided with means 100 for consecutively establishing one in front of the other a plurality of magnetic fields, a projectile guide encircled by said fields, the latter having their lines of greatest force arranged spirally around the axis of the 105 guide, and a projectile having spirally arranged portions arranged to correspond respectively with and to be operated upon by said spiral lines of force.
13. A magnetic gun provided with a sole- 110 noid coil which forms a guide for a magnetizable projectile and having means for forming a spiral magnetic field, means for energizing the coil prior to the entrance of the projectile, and means by which the coil is deenergized prior to the exit of the projectile.
14. A magnetic gun provided with a sole- 115 noid coil which forms a guide for a magnetizable projectile, and having means for forming a spiral magnetic field, means con- 120 trolled by the projectile for energizing the coil prior to the entrance of the projectile, and means controlled by the projectile by which the coil is deenergized prior to the exit of the projectile.
15. A magnetic gun provided with a plu- 125 rality of solenoid coils which form a guide for a magnetizable projectile, and having means for forming a spiral magnetic field, means by which the coils are consecutively energized prior to the entrance of the projectile therein, and means by which the coils are consecutively deenergized prior to the exit therefrom of the projectile.
16. A magnetic gun provided with a plu- 130 rality of solenoid coils which form a guide for a magnetizable projectile and having means for forming a spiral magnetic field, means controlled by the projectile for consecutively energizing the coils prior to the entrance therein of the projectile, and means controlled by the projectile by which the coils are consecutively deenergized prior to the exit of the projectile therefrom.
17. A magnetic gun provided with a twisted polygonal barrel, and a helix encir- 135 cling and conforming to the barrel.
18. A magnetic gun provided with a twisted polygonal barrel, a helix encircling and conforming to the barrel, and means controlled by a magnetizable projectile for energizing the helix.
19. A magnetic gun provided with a twisted polygonal barrel, a plurality of helices encircling and conforming to the barrel, and means controlled by a projec- 140 tile for consecutively energizing the helices.
20. A magnetic gun provided with a twisted polygonal barrel, a plurality of helices encircling and conforming to the barrel, means controlled by a projectile for consecutively energizing the coils prior to the entrance of the projectile, and means controlled by the projectile by which the coils are consecutively deenergized prior to the exit of the projectile therefrom.
21. A magnetic gun provided with a barrel having a circular longitudinal opening therethrough, the barrel being polygonal in cross section, the sides of the barrel being disposed spirally and a helix encircling and conforming to said barrel.
22. The combination with a gun having means for forming a spiral magnetic field, of a projectile having a spiral magnetic rib adapted to coöperate with said spiral mag- 150 netic field.
23. The combination with a gun having a projectile guide and electro-magnetic field producing means, of a projectile adapted for travel and rotation in said guide, said projectile guide, projectile and electro-magnetic field producing means being constructed and arranged to cause the projectile to be projected and rotated electro-magnetically.
24. A gun having a projectile guide and 155

electromagnetic field producing means, the
guide and electro-magnetic field producing
means being constructed and arranged to
project and rotate electro-magnetically a
5 suitable projectile.

25. A gun having a projectile guide and
means for forming a spiral electromagnetic

field arranged and constructed to project
and rotate electromagnetically in said guide
a suitable projectile.

In testimony whereof I have signed my
name to this specification.

CHARLES E. MORRIS.
